US0D1038122S

(12) **United States Design Patent** (10) **Patent No.:** **US D1,038,122 S**
(45) **Date of Patent:** ** **Aug. 6, 2024**

(54) **DISPLAY DEVICE**

(71) Applicant: **Google LLC**, Mountain View, CA (US)

(72) Inventors: **Carl Cepress**, Mountain View, CA (US); **Matthew Seflic**, San Jose, CA (US); **Maj Isabelle Olsson**, Sunnyvale, CA (US); **James Castro**, San Jose, CA (US); **Katherine Morgenroth**, San Mateo, CA (US)

(73) Assignee: **Google LLC**, Mountain View, CA (US)

(**) Term: **15 Years**

(21) Appl. No.: **29/806,554**

(22) Filed: **Sep. 3, 2021**

Related U.S. Application Data

(63) Continuation of application No. 29/663,723, filed on Sep. 18, 2018, now Pat. No. Des. 934,244.

(51) **LOC (14) Cl.** **14-02**

(52) **U.S. Cl.**

USPC **D14/374; D14/371**

(58) **Field of Classification Search**

USPC D14/125–126, 129–130, 133, D14/140.1–140.2, 140.5, 203.7–203.8, D14/214, 307, 336, 371–372, 374–380, D14/388–389, 448, 900, 902, 341; D18/4.3–4.5, 12.3; D21/324, 329, 332; D24/160, 186

CPC G06F 1/1637; G06F 1/1626; G06F 3/167
See application file for complete search history.

(57) **CLAIM**

The ornamental design for a display device, as shown and described.

DESCRIPTION

FIG. 1 is a perspective view of a display device showing our design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

In the drawings, the broken lines illustrate portions of the display device that form no part of the claimed design.

1 Claim, 3 Drawing Sheets
